APPARATUS FOR REFINING OIL

Original Filed Oct. 13, 1919

UNITED STATES PATENT OFFICE

CHAUNCEY B. FORWARD, OF URBANA, OHIO, ASSIGNOR, BY MESNE ASSIGNMENTS, TO FORWARD PROCESS COMPANY, OF DOVER, DELAWARE, A CORPORATION OF DELAWARE

APPARATUS FOR REFINING OIL

Application filed October 18, 1919, Serial No. 330,490. Renewed November 22, 1927.

My invention relates to an apparatus for refining petroleum, and in general my object is to provide a set of instrumentalities adapted to work together with the maximum efficiency in separating a high percentage of light volatile oils from a heavy mineral oil without impairing the qualities or values of the various hydrocarbons composing the oil. This general object is largely attained by forcing a stream of mineral oil continuously through a series of coils of small pipe contemporaneously with the constant forced delivery of a stream of water through other coils of pipes in a flash boiler where the flowing water is rapidly converted into superheated steam which is applied immediately in full volume and continuously to the coils of pipe through which the stream of oil and vapors are flowing, thereby heating and vaporizing the oil in a high degree and further superheating the vapors with a minimum consumption of fuel.

In the sheet of drawing accompanying this application I show a diagram of an apparatus constructed according to my invention, which apparatus comprises a steam pump 2 adapted to force a stream of mineral oil from any given source of supply continuously through a line of pipe 3 of relatively small diameter but of great length and compactly formed into a series of coils 4 and 5 separately confined in closed cylinders 6 and 7, respectively, hereinafter referred to as the first and second oil preheaters. A second steam pump 8 is adapted to force water into a tank 9 and maintain the requisite pressure to deliver a constant stream of water through a coil of pipe 10 removably supported in sections within the combustion chamber and flue spaces of a furnace 11, which in its entirety may be termed a flash boiler. A valve 12 and a water meter 13 are provided at the intake end of this coil of pipe 10 to regulate the flow of water according to given needs, and a safety or blow-off valve 14 is connected with the coil 10 at approximately its middle or where the water is practically all converted into steam. The lower sections of coil 10 are exposed to the flames of the fuel-oil burner 15

and the steam generated in the upper sections of the coil is superheated in the lower sections and continuously discharged therefrom at extremely high temperatures, and where occasion requires above 1000° F. 55

The superheated steam is utilized in full volume as rapidly as it is produced, that is, it is conveyed directly by insulated pipes 16 to the second oil preheating cylinder 7, thence by pipe 17 to the first oil preheating cylinder 6, and thence by pipe 18 to a drum 19 where the steam, less the superheat, is available in large volume for use in the pumps, in heating the buildings, and in operating other apparatus in the plant. A 65 higher temperature is maintained constantly in the second oil heater 7 than in the first oil heater 6, because the flow of steam is inverse to the flow of oil, and the pressure in the drum, when the steam is not being used 70 rapidly enough for other purposes about the plant, is regulated by a relief valve to not exceed 100 to 125 pounds in order that the superheated steam originally introduced into preheaters 6 and 7 at a much higher 75 pressure may flow freely through the heating cylinders and their pipe connections, and the flow of steam from preheaters 6 and 7 may also be under valve control.

The oil flowing through coils 4 and 5 is 80 thus gradually heated to a high degree without detriment to its hydrocarbon constituents and is jetted in a continuous stream with its volatilized portions or vapors through a nozzle 20 into a closed vessel 21 together with 85 superheated steam derived from flash boiler 11 and conveyed to nozzle 20 by way of a branch pipe 22 and other channels as hereinafter more fully described. Both the oil and steam are under pressure traceable back 90 to the two pumps and the flash boiler, a high pressure is constantly maintained in the closed vessel 21, the high heated oil and vapors are atomized by the introduction of the steam through nozzle 20, and the steam so 95 introduced maintains a high temperature and pressure within this vessel; thereby effecting a high percentage of separation of the volatile portions of any given mineral oil, varying of course with the kind or grade of oil 100

being treated. The liquid derivative flows unaltered in composition from the bottom of vessel 21 into a well 23 having a sight gauge and thence passes under restricted pressure from closed vessel 21 and well 23 through a pipe line to a tank 24 located at a distant point. As the flow of oil from the pump is always the same and the temperature and pressure constant, the unvaporized portion of the oil is always constant at this point so that the valve may readily be adjusted to maintain a steady level of the unvaporized oil in well 23 and the operation is thus automatic in this respect as well as in other respects.

The volatilized product in vessel 21, together with superheated steam, is forced through a pipe 25 into and through one or more heating coils 26, 27 and 28 confined in separate insulated cylinders 29, 30 and 31, respectively, and a high temperature is maintained in each cylinder by superheated steam obtained through separate valved pipe connections 32 with the discharge pipe 16 of flash boiler 11. The steam in the vapor heaters 30 and 31 is conveyed under high pressure and temperature through a set of connected pipes 33 direct to the first oil preheater 6, and this steam from the vapor heaters 30 possesses a higher temperature than the steam derived from the second oil preheater 7 because it is only used to raise the temperature of the hot volatilized product discharged from the separation vessel 21. Consequently the said arrangement is of decided advantage in maintaining a high temperature in the first oil preheater and a more rapid heating of the oil from its cold state. I also utilize a portion of this steam at high temperatures in effecting the separations in vessel 21, that is, the branch pipe 22 is connected with pipe 33 which conveys the steam from two of the vapor heaters to the first oil preheater 6. The steam in the first vapor heater 29 may be discharged into the first oil preheater 6 before being discharged to drum 19, but is preferably conveyed directly to said drum by way of a separate pipe 34.

By the instrumentalities described a large portion of the oil will be volatilized or reduced to a vapor, and the volatilized product separated from the unvolatilized product in the separating vessel 21. This heated volatilized product is then heated to a higher temperature, or superheated in the vapor heaters, thereby converting it into a more volatile product so that when it is condensed subsequently a very high percentage of gasoline or motor fuel content can be separated therefrom. There are other advantages derived by superheating the vapors, among which is the self-removal of the free carbon from the vapors, and which residue is trapped in a clean-out receptacle 35 through which the volatile product must pass by way

of the coil-connecting pipe 36 before discharging through pipe 37 into the lower end of a condensing cylinder 38. A second clean-out receptacle 39 has a valved pipe-connection 40 with the bottom of receptacle 35 and the contents of these receptacles can be drained into a storage tank 41 without interrupting operations.

The rapidity with which the oil and vapors are forced through the relatively small pipes of the coils does not permit the carbon which is freed to adhere to the inner side of the coils or coke and foul the pipes; and because the residue from separator 21 is not subjected to the high temperatures used in and for the vapor heaters, the residue is in better condition for further refining than it can possibly be gotten where a similar quantity of volatile separations have been effected by distillation by direct heat from a fire, or by other steps known to me. No cooking or carbonization of the oil occurs because no direct flame or fire is applied to the oil or vapor conveying pipes and vessels, thus avoiding the so-called local heat spots, and only the pipe sections through which the water flows in the flash boiler is subjected to the direct action of fire or flames.

The volatile product from clean-out receptacle 35 passes upward through condensing cylinder 38 in which a constant spray of water is delivered in measured amounts through a spray pipe 42, and the volatilized product which is not condensed is carried under the sustained pressure in the system through an outlet pipe 43 into a worm condenser 44. The water spray reduces the temperature of the vapors and by regulating the amount of water the heavier end of the resultant gasoline or motor fuel oil may be cut out by condensation, and the gravity or end point by distillation controlled to suit the operator. The product coming from the worm condenser is a water-white motor fuel oil or gasoline which is discharged with the condensed steam into a separator 45, the water outlet at the bottom being controlled by an automatic float valve and the oil overflows from above into a large receiver 46 before it is discharged into a storage tank 47 by the automatic operation of a pump 48 controlled by a steam valve V and a float 49 in receiver 46. The gasoline or motor fuel is at this point ready for the market, that is, it requires no further treatment.

The unvaporized products and the water sprayed into the cylinder 38 pass out of a bottom connection into a sight well 50, and a valved pipe 51 connects this well with a water-cooled coil 52 which is adapted to discharge the mixed liquid into an automatic separator 53 having a float controlled valve at the bottom for the water and an oil overflow connection with a receiver 54. When a predetermined quantity of the oil fractions

are trapped in receiver 55 it is automatically and without shutting down the installation for repairs. The lower pipes of the superheater for the steam are practically the only places at which there is any wear and tear, and these pipes can be quickly replaced at a nominal cost. The remainder of the apparatus is not subjected to direct fire, nor affected materially by constant use in practicing the process, which process is further disclosed and also claimed in my application, filed Aug. 19, 1919, Ser. No. 318,484. 70

5 The most economical sized apparatus or unit for commercial use will refine approximately 150 barrels of oil per day, and where a series of say five or more such units are used in one plant the superheated steam subsequent to its use may be reheated by a coil in a small furnace and used again in successive units repeatedly. However, by the use of a flash boiler as herein disclosed I effect great economy in operations as very little 75

10 if any additional fire is required to create the steam as well as superheat it to the desired temperature. Thus in order to superheat the steam to the desired temperature it is only necessary to have the superheating 15 or final pipe sections of the coil relatively near the fire, while the more remote sections of the coil convert the flowing water into steam as rapidly as it is forced through the coil. My prior practice has been to use a 20 boiler in which a large body of water was heated and a large volume of steam stored and superheated, but while the maintenance of a large body of steam in a boiler may be necessary where fluctuating demands require 25

20 an excess of steam, I find that the production and storing of steam in that manner is not an economical mode or best adapted for the purposes of refining oil by the use of superheated steam. This is obvious when 30

30 comparison is made with the present apparatus in which a flash boiler is used and the flowing water is immediately converted into a tenuous stream of superheated steam which is not permitted to accumulate in large 35

35 volume with a large body of water requiring intensive firing, but is immediately conveyed under pressure to the oil and vapor heating cylinders where conduction of the superheat to the oil is quick and responsive. In this 40 connection it is important to note that the oil and water are both under constant pressure until both reach a common destination in a modified form as effected by the flash boiler and oil heaters operating together to that 45 single end. In the operation of a large refinery where tanks of boilers are required to provide steam for the various operations in the plant, the economy in the use of this 50 apparatus is obvious as the steam has been created cheaply to start with and is practically all available for other purposes after it has served its purpose in treating the oil by this apparatus. 55

In an installation involving a series of 60 apparatus as described I would also include a reserve flash boiler which could be used whenever the pipes or coils in any one of the 65 regular series of flash boilers required replacement or repair, and in this way continue the operation in each apparatus uninter-

In an installation using plural apparatus of the kind herein described I would conduct the vapors from all of them to a single carbon remover, single water spray condenser and single worm condenser, thus simplifying the operation and reducing the cost of construction. 80

The apparatus will operate continuously 85 and automatically for indefinite periods as there is no stopping to cool down and remove carbon or coke as in all other apparatus known to me. 90

What I claim is:

1. An apparatus for refining oil, comprising a flash boiler having a water and steam pipe adapted to generate super-heated steam continuously, in combination with an oil heater in open connection with said boiler, 95 a steam drum in open receiving communication with said heater, a pump adapted to force water continuously through said boiler, means adapted to regulate the steam pressure within said drum, and means adapted to maintain a common pressure in said drum and said water and steam pipe back through the boiler to promote a constant flow of water through said boiler and a continuous supply of superheated steam within said heater 100 under high pressure and temperature. 105

2. An apparatus for refining oil, comprising a number of oil pre-heaters and a vapor and liquid separating-vessel and a number of vapor heaters connected in series, and a flash-boiler having superheating steam coils connected with both sets of heaters, and said vapor heaters having a steam discharge connection opening into the first of said oil pre-heaters. 110 115

3. An apparatus for refining oil, comprising a steam cylinder and an oil-heating coil therein, an oil and vapor separating vessel connected with said coil, a steam cylinder having a vapor heating coil in receiving connection with said separating vessel, a flash-boiler having steam superheating coils in discharging connection with said vapor heating cylinder, and a steam discharge connection 120 for said vapor heating cylinder having a return connection leading to said separating vessel. 125

4. In an apparatus for cracking hydrocarbon oils, the improvement comprising a continuous elongated heating coil consisting of 130

- a plurality of coil sections mounted in separate heating chambers and connected in series, means for supplying oil to one end of said coil, a second continuous elongated heating coil consisting of a plurality of coil sections mounted in separate heating chambers and connected in series to form a single coil, means for supplying vapors from the first said heating coil to the second heating coil, means adapted to flow a heating medium in aeriform condition from a common source in heat exchanging relation directly with a plurality of the coil sections of the second said heating coil along paths arranged in multiple, and means adapted to flow a heating medium in aeriform condition serially over the plurality of the coil sections of the first said heating coil. 5. In an apparatus for cracking hydrocarbon oils, the improvement comprising a continuous elongated heating coil consisting of a plurality of coil sections mounted in separate heating chambers and connected in series, means for supplying oil to one end of said coil, a second continuous elongated heating coil consisting of a plurality of coil sections mounted in separate heating chambers and connected in series to form a single coil, means connected with the first said heating coil adapted to separate vapors and liquid, connections adapted to supply vapors from said vapor and liquid separating means to the second said heating coil, means adapted to flow a heating medium in aeriform condition from a common source in heat exchanging relation directly with a plurality of the coil sections of the second said heating coil along paths arranged in multiple, and means adapted to flow a heating medium in aeriform condition serially over the plurality of the coil sections of the first said heating coil. 6. In an apparatus for cracking hydrocarbon oils, the improvement comprising a continuous elongated heating coil, consisting of a plurality of coil sections mounted in separate heating chambers and connected in series, means for supplying oil to one end of said coil, a second continuous elongated heating coil consisting of a plurality of coil sections mounted in separate heating chambers and connected in series to form a single coil, means for supplying vapors from the first said heating coil to the second said heating coil, means adapted to flow a heating medium in aeriform condition from a common source in heat exchanging relation directly with a plurality of the coil sections of the second said heating coil along paths arranged in multiple and thereafter over at least a portion of the first said heating coil. 7. In an apparatus for cracking hydrocarbon oils, the improvement comprising a continuous elongated heating coil consisting of a plurality of coil sections mounted in separate heating chambers and connected in series, means for supplying oil to one end of said coil, a second continuous elongated heating coil consisting of a plurality of coil sections mounted in separate heating chambers and connected in series to form a single coil, means connected with the first said heating coil adapted to separate vapors and liquid, connections adapted to supply vapors from said vapor and liquid separating means to the second said heating coil, means adapted to flow a heating medium in aeriform condition from a common source in heat exchanging relation directly with a plurality of the coil sections of the second said heating coil along paths arranged in multiple and thereafter over at least a portion of the first said heating coil. Signed at Urbana, in the county of Champaigne, and State of Ohio, this 9th day of October, 1919.
